UNITED STATES PATENT OFFICE.

ABRAHAM ESAU, OF JENA, GERMANY.

ANTENNA ARRANGEMENT FOR SHORT-WAVE APPARATUS.

Application filed October 8, 1926, Serial No. 140,378, and in Germany October 7, 1925.

This invention relates to antenna arrangements particularly for short-wave apparatus.

In known short-wave apparatus the antenna is connected to the oscillation circuit either inductively or through capacity. In accordance with my invention the antenna is connected by a metallic conductor. Experiments with antennæ of this kind have shown that the best radiation of short-waves is obtained when the connection of the wave carrying member or coil of the oscillation circuit to the earth through a conductor or condenser is omitted and the antenna is connected to a node of voltage in a wave carrying member of the apparatus.

A further feature of the invention consists in the connecting of a plurality of antennæ to a number of nodes of voltage whereby a reflecting member associated with the antenna proper is obtained.

The aforementioned experiments have also shown that oscillations in the apparatus will only commence if the length of the antenna is equal to a quarter of a wave length or to an uneven multiple of same. If the antenna length differs from these values the oscillations cease. I employ this fact as a means for controlling the radiated energy of short-wave senders by changing the length of the antenna at will. This is preferably effected by adding or subtracting a section of the antenna by means of a key, switch or the like. An advantage gained hereby is that there is no consumption of energy in the intervals between the closures of the signalling key.

The invention is illustrated in the drawing in which Fig. 1 shows an arrangement in which one antenna is employed while Fig. 2 shows an arrangement in which a plurality of antennæ are used.

In both figures, which show oscillation producers, 11 denotes the source of anode current, D_1 and D_2 are high frequency chocking coils, R is a non-inductive resistance, W a heating current resistance, and E the heating or filament battery. C is a condenser and L a wave carrying member or coil of the oscillation circuit. In the wave carrying coil L of Fig. 1 there is a node of volt-

age a_1 to which the antenna A is connected. In the wave carrying coil L of Fig. 2 there are two nodes of potential a_2 and a_3 to which the antennæ A_1 and A_2 are connected. To enable the length or lengths of the antenna or antennæ to be changed they may be made of sections. In the drawing sections A_2 are shown that can be connected to and disconnected from the antenna proper by means of keys or switches T . By thus adding to or subtracting from the length of the antenna the results hereinbefore mentioned are obtained.

I claim:

1. Antenna arrangement for short-wave radiation, comprising a closed oscillation circuit including a wave-carrying coil isolated from the earth, and a wave radiator in direct conducting connection with a node of voltage of the wave carrying coil in said closed circuit.

2. Antenna arrangement for short-wave radiation, comprising a wave-carrying coil insulated from the earth, and wave radiators in direct conducting connection with nodes of voltage of the wave-carrying coil, whereby a reflecting member associated with an antenna member is obtained.

3. Antenna arrangement for short-wave radiation, comprising a closed oscillation circuit including a wave-carrying coil isolated from the earth, and wave-radiators in direct conducting connection with nodes of voltage of the wave-carrying coil in said closed circuit, whereby a reflecting member associated with an antenna member is obtained.

4. Antenna arrangement for short-wave radiation, comprising a closed oscillation circuit including a wave-carrying coil isolated from the earth, a section of antenna in direct conducting connection with a node of voltage of the wave-carrying coil in said closed circuit, another section of antenna, and a device for connecting and disconnecting said sections, whereby the radiation is controlled.

In testimony whereof I have affixed my signature.

ABRAHAM ESAU.
